Primary Examiner — Jennifer L Watkins(74) *Attorney, Agent, or Firm* — Knobbe, Martens, Olson & Bear, LLP(57) **CLAIM**

The ornamental design for a scar therapy patch, as shown and described.

DESCRIPTION

FIG. 1 is a front view showing a scar therapy patch of our design;

FIG. 2 is a rear view thereof;

FIG. 3 is a left side view thereof;

FIG. 4 is a right side view thereof;

FIG. 5 is a top view thereof and,

FIG. 6 is a bottom view thereof.

Broken lines illustrate portions of the scar therapy patch that form no part of the claimed design.

1 Claim, 4 Drawing Sheets(56)
